JESUS VIRAMONTES, OF SANTA PAULA, CALIFORNIA

IGNITION APPARATUS

Application filed September 12, 1929. Serial No. 392,047.

This invention relates to an improved ignition apparatus for internal combustion engines.

The primary object of the present invention is to provide a simple and efficient ignition system or apparatus for use on multiple cylinder internal combustion engines of the valve-in-head type, and by means of which the charges are ignited at the completion of 10 the compression strokes without employing timing devices or expensive and complicated electrical devices and wiring.

The invention consists in the novel form, combination and arrangement of parts hereinafter more fully described, shown in the accompanying drawings, and claimed.

In the drawings:

Figure 1 is a side elevational view of an internal combustion engine equipped with 20 an ignition apparatus embodying the present invention, a portion of the apparatus being omitted.

Figure 2 is a vertical transverse section taken substantially on line 2—2 of Figure 1.

Figure 3 is an enlarged perspective view of one of the spring contacts carried by the rocker arms as shown in Figures 1 and 2; and

Figure 4 is a wiring diagram illustrating the complete ignition apparatus as 30 operationally associated with the engine of Figure 1.

In the accompanying drawings, the ignition apparatus is shown applied to an internal combustion engine having four cylinders 5, 6, 7, and 8 covered by a head 9 which carries 35 the usual spring seated valves for controlling the admission of charges to and the exhaust of spent gases from the cylinders. Each cylinder has one exhaust valve and one intake valve, and these valves are opened at timed intervals by the usual valve operating mechanism including vertical push rods 10 and rocker arms 11, each rocker arm bearing at one end on the upper end of one of said 40 push rods and at the other end on the upper end of the stem 12 of the associated valve. The push rods 10 are vertically reciprocated in the usual way by operative association 45 with the usual cam shaft, not shown. Only 50 the intake valves are shown in order to dis-

close an embodiment of the present invention, and these are indicated at 13.

The usual spark plugs are provided for the cylinders, and each plug is composed of an outer metallic casing 14 having a threaded 55 end for being screwed into an opening in the head 9. This casing has the usual ground terminal 15, and is provided with a bore which receives an insulating body 16. The body 16 in turn has a central bore which receives a central electrode or conductor rod 17 whose inner end forms the terminal 18 disposed in spaced relation to the terminal 15 to form a spark gap between itself and the latter.

In accordance with the present invention, 60 a bar 19 of insulating material is mounted above the rocker arms 11 and has fixed contacts 20 exposed at the under side thereof in position to co-act with spring contacts 21 carried by certain of the rocker arms 11 to 65 successively place the spark plugs in circuit with an ignition coil 22 for firing the compressed charges of the cylinders in proper sequence. The coil 22 is of that type employing a continuously-acting vibrator, such 70 as are used on model T Ford automobiles, and shown for example in the U. S. Letters Patent to J. F. Cavanagh, No. 1,034,583, dated 75 August 6, 1912. As shown, a contact 21 is mounted on and insulated from the rocker 80 arm for the intake valve 13 of each cylinder, and adjacent the end of said rocker arm which bears on the associated push rod 10. One terminal of the coil 22 is connected by 85 a conductor wire 23 with all of the contacts 21, the other terminal of the coil being grounded as at 24. The contact 20 which co-acts with the contact 21 carried by the rocker 90 arm 11 for the intake valve of cylinder 5 is connected by a conductor wire 25 with the central electrode 17 of the spark plug for cylinder 7, the next contact 20 being similarly 95 connected to the spark plug of cylinder 5 by a conductor wire 26, the following contact 20 being likewise connected by a conductor wire 27 to the spark plug of cylinder 8, and the remaining contact 20 being connected by a conductor wire 28 to the spark plug of cylinder 6. In other words, the arrangement 100 is such that when the rocker arm for the in-

take valve of each cylinder operates to open said valve and admit a charge, it closes the circuit to the spark plug of another cylinder in which a charge has been admitted and compressed, this insuring ignition of the charges 5 at the proper time at all engine speeds and without employing a timing device. The current flows, of course, from the terminal 15 of each spark plug to the grounded terminal 10 of the coil 22, the terminal 15 being electrically connected to the cylinders, and the latter being grounded as at 29.

The coil 22 is included in a primary circuit with a battery 30 and a switch 31, as usual.

15 The contacts 20 are preferably formed by the heads of bolts passed through the bar 19 and having nuts 32 threaded on their upper ends for clamping the ends of the wires 25, 26, 27 and 28 thereto. The contacts 21 are 20 preferably in the form of U-shaped clips bolted to the rocker arms 11 and having yielding tongues arranged to engage the contacts 25, so that final movement of the rocker arms will be permitted after engagement of said contacts 21 with contacts 20 without causing 30 breakage of the bar 19. The movement of each rocker arm 11 to permit closing of the associated valve 13 results in promptly opening the circuit to the associated plug of another cylinder until that cylinder again has a charge compressed therein ready for firing.

From the above, it will be seen that by means of the present invention the wiring is simplified and reliable operation is insured 35 with little danger of ignition troubles.

What I claim as new is:

1. The combination with a multiple cylinder internal combustion engine of the valve-in-head type, wherein said cylinders are provided with intake and exhaust valves operated by means including push rods and rocker arms, of an ignition apparatus for said engine comprising a spark plug for each cylinder, a contact mounted above the rocker arm for one valve of each cylinder, said contacts each being electrically connected with the central electrode of the spark plug for another cylinder, a further contact carried by each of the last named rocker arms, each 40 of said further contacts being arranged to engage one of the first named contacts upon the valve-opening movement of the rocker arm which carries the same, and a source of ignition current having one terminal connected with all of said further contacts.

2. In an ignition apparatus for multiple cylinder internal combustion engines of the valve-in-head type, a plurality of contacts, one carried by the rocker arm for one valve 45 of each cylinder, and further fixed contacts, each connected to the spark plug of one cylinder and arranged to co-act with a contact carried by the rocker arm for a valve of another cylinder for controlling the flow of ignition current to said plug.

3. The combination with a multiple cylinder internal combustion engine of the valve-in-head type, wherein said cylinders are provided with intake and exhaust valves operated by means including push rods and rocker arms, of an ignition apparatus for said engine comprising a spark plug for each cylinder, a contact mounted above the rocker arm for one valve of each cylinder, of said contacts each being electrically connected with the central electrode of the spark plug for another cylinder, a further contact carried by each of the last named rocker arms, each of said further contacts being arranged to engage one of the first named contacts upon the valve-opening movement of the rocker arm which carries the same, and a source of ignition current having one terminal connected with all of said further contacts, and a bar of insulating material mounted on the engine above said rocker arms and carrying the first named contacts.

4. The combination with a multiple cylinder internal combustion engine of the valve-in-head type, wherein said cylinders are provided with intake and exhaust valves operated by means including push rods and rocker arms, of an ignition apparatus for said engine comprising a spark plug for each cylinder, a contact mounted above the rocker arm for one valve of each cylinder, of said contacts each being electrically connected with the central electrode of the spark plug for another cylinder, a further contact carried by each of the last named rocker arms, each of said further contacts being arranged to engage one of the first named contacts upon the valve-opening movement of the rocker arm which carries the same, and a source of ignition current having one terminal connected with all of said further contacts, and a bar of insulating material mounted on the engine above said rocker arms and carrying the first named contacts, the second-named contacts being yieldable in a direction parallel with the direction 95 of movement of said rocker arms.

5. In an ignition apparatus for multiple cylinder internal combustion engines of the valve-in-head type, a plurality of contacts, one carried by a movable member of the operating means for one valve of each cylinder, and further fixed contacts, each connected to the spark plug of one cylinder, and arranged to co-act with a contact carried by the movable member of the valve operating means of another cylinder, for effecting the flow of ignition current to the spark plugs of said cylinders in proper sequence.

In testimony whereof I affix my signature.
JESUS VIRAMONTES.
